UNITED STATES PATENT OFFICE.

GAIUS C. FULLER, OF CINCINNATI, OHIO, ASSIGNOR TO THE G. C. FULLER MANUFACTURING COMPANY, OF CINCINNATI, OHIO, A CORPORATION OF OHIO.

GASLIGHTER.

1,386,563.

Specification of Letters Patent.

Patented Aug. 2, 1921.

Application filed December 19, 1919. Serial No. 346,117.

To all whom it may concern:

Be it known that I, GAIUS C. FULLER, a citizen of the United States, residing at Cincinnati, in the county of Hamilton and State of Ohio, have invented certain new and useful Improvements in Gaslighters, of which the following is a specification.

My invention relates to improvements in lighters of the kind in which sparks are produced by abrasion or friction.

The object of my invention is to provide for the ready renewal of the spark-producing material without providing each renewal with a separate holder; and to readily adjust or feed the material to the abradant, so as to utilize practically all of the material, to increase the efficiency of the spark, and to minimize the wear upon and the clogging of the abradant, so as to in general provide a more efficient and economical means for ignition of combustible gases. Other objects will appear in the course of the ensuing description.

I attain these objects by the device illustrated, for example, in the accompanying drawing, in which—

Figure 1 is a perspective view of a gaslighter embodying my invention;

Fig. 2 is a partial similar view showing a slight modification;

Fig. 3 is a vertical longitudinal section of the holder with its screw and the spark material therein in elevation, and with a cross-section of the abradant element in its relation to the spark element;

Fig. 4 is a view similar to Fig. 1, but from the opposite side, and showing the gaslighter open;

Fig. 5 is a section like Fig. 3, but showing the positions of the parts when the spark material is nearly all consumed;

Fig. 6 is a detail view, corresponding to Figs. 3 and 5, of the holder with its screw and the spark material omitted, to more clearly show the interior arrangement of the holder;

Fig. 7 is a sectional view similar to Fig. 3, but showing a modification;

Fig. 8 is a partial perspective view, corresponding to Figs. 1, 2 and 4, but showing the modification of Fig. 7;

Fig. 9 is a detail of the blank from which the holder of Figs. 7 and 8 is formed;

Fig. 10 is a section similar to Fig. 3, but showing another modification; and

Fig. 11 is a cross-section on a plane corresponding to the line 11—11 of Fig. 10.

As I prefer to construct my invention, there is a handle comprising the members 1 and 2 branching forwardly from the junction spring 3. The member 1 has the wide U-shaped abradant holder 4 on its free end, and has the down-turned loop 5 some distance back from the holder 4. The member 2 has the up-turned loop 6 some distance back from its free end, on which end is mounted the spark-producing material, as will presently be described. This handle is formed of a single piece of wire coiled and bent to form the several parts just mentioned; and the member 2 is acted upon by the junction spring 3 so that it not only presses laterally outward against the terminal stud 4' of the abradant holder 4 at the left, but also tends or presses toward the holder 4 to press the spark-producing material against the abradant. The opposite loops 5 and 6 afford thumb or finger engaging means, so that the manual pressure is directed toward the abradant and increases the pressure of the spark-producing material against the abradant as the handle members are manually pressed toward each other to drag the spark-producing material across the abradant, whether the lighter be held with the abradant faced upward, as shown, or faced downward, as it usually is in practice. This provision of the loops at both sides is of especial advantage when the member 2 is raised considerably from the abradant by the extension of a new supply of spark-producing material from its holder, as is peculiar to my improved holding means now to be described.

The holder for this material has heretofore been permanently secured to the material and removable from the handle part and discarded therewith, or it has involved some other complication by which the hereinbefore mentioned objects of the present invention are not attained.

My improved holder 7 is permanently attached to the end of the member 2, by means of its horizontal neck 8 receiving the end tightly therein. Its forward vertical barrel 9 has an opening vertically through it, which is threaded throughout a minor upper portion 10 (Fig. 6) and smooth throughout a major lower portion 11, the diameter of this lower portion 11 being sufficient to admit

freely the screw 12 that is screwed down through the threaded upper portion 10. This screw may have the knurled head of Figs. 1, 3, 4 and 5, or the slotted head as on the screw 12' of Fig. 2; or it will be understood that any other variation of this part of the screw will not be a departure from my present invention.

The screw 12 and the portions 10 and 11 of the opening are so proportioned that the screw 12 will turn rather freely in the portion 10 and so that the lower portion 11 may have the cylindrical piece 13 of spark-producing material fitted snugly but slidably therein, with its upper end bearing against the lower end of the screw 12 and with its lower part projecting down out of the bottom of the barrel 9 of the holder 7, and its lower end bearing upon the abrasive element 14, which is a small flat file notched at its ends to fit around the holder stud 4' and the bent-down part 4'', which has a slight projection 4''' over this end of the file 14 to hold this end down. The other end is held down by the constant pressure of the handle spring-member 2, pressing the spark-producing material 13 onto the file. The file 14 may be toothed on both sides, and turned over to present a new abrading surface. These details of the file and the means of holding it are themselves not original herein. The novelty is in the just-described relation of the spark-producing material to this file and in the handle member 2 that presses it against the file.

Generally, this material in the piece 13 is a pyrophoric alloy, as is commonly employed in gas lighters. This is the material which I prefer to employ; and it is very expensive. The value of this small piece of alloy is about as much as that of all of the other parts of the device combined.

By virtue of my improvement, combining the constant spring-pressure of the member 2 with the positive adjustment of the material 13 in its projection down from the holder 7 on the end of this arm or member 2, the material can, by an occasional manual adjustment of the screw 12 or 12', be utilized in its entirety, until the full length of Fig. 3 has been worn down to a thinness sufficient only for producing the last spark, as illustrated, in somewhat exaggerated form, in Fig. 5. And, except after the piece has become worn very short, the material can be kept projected an ample distance past the bottom of the holder 7, so that there is sufficient space all around and above the zone of abrasion to permit free escape of the incandescent particles and gases, or sparks, into the gas to which the lighter is applied. Also, since the bottom of the holder 7 never is permitted to contact with the file surface, except possibly in the very last stages of use of the piece of material, as in Fig. 5, there is

practically no wearing away of the holder material to clog the teeth of the file, and no wear on the file other than that incident to the abrasion of the material 13, as intended. The pyrophoric alloy is not so hard as to unduly wear the file; yet is not so soft as to appreciably clog the file teeth. This is an economy in the supply of the files, as well as in the supply of the sparking-material and in the efficiency of use of both.

Where the sparking material is permanently secured in a holder, the latter is detachable from the member 2, and is discarded when the sparking material therein has been worn off until none of it projects from the bottom of the holder. This is usually about half of the length of the piece of material, so that there is about fifty per cent. waste of this valuable material; and there is one hundred per cent. waste of the holder thus discarded. Moreover, the user will neglect renewal after the material is thus worn down, and continue to drag the bottom of the holder across the file, thus obtaining a very poor spark, because the spark is smothered by the close contact of the holder bottom. As these holders are usually of some very soft metal, such as lead, a few such operations as this are sufficient to render the file practically useless, even with renewed holder and sparking material, because its teeth are clogged with the soft metal thus worn from the holder, which should have been discarded. Then the user, to further utilize the lighter, must not only renew sparking material and holder, but also the file.

With my improvement, the manual, positive adjustment of the sparkling material is so convenient—involving a mere slight turning of the screw 12 or 12' occasionally—that there is little tendency for neglect to renew; so that the detriment of the other lighters, as just alluded to, is practically eliminated. And knowing the convenience of this adjustment, the user will not neglect to use it in fully projecting the sparkling material until it is all worn away and utilized, as before mentioned. The saving thus attained, amounting to the full value of the entire device in a comparatively short time, is relatively very important.

In practice, I prefer to mold the holder 7 of a soft, readily fusible metal, such as lead or some alloy thereof, with the end of the member 2 lying in the neck part of the mold, and one of the screws 12 or 12', or a similarly threaded core, lying, in alinement with a smooth core for the smooth part 11, in the barrel part of the mold. The neck part is left attached to the member 2, as results from this process; and the smooth core is withdrawn and, if one of the screws 12 or 12' has been inserted instead of a special threaded core, this screw is left in the

casting, merely withdrawing the smooth core, leaving the space in which the sparking material is placed. If a piece of this material is used as the smooth core, it may 5 be left in place. Thus it will be seen that the device can be taken from its mold in more or less complete condition, not only of formation, but of assembly, permitting of economy in manufacture. But it will be understood also, that these parts may be differently formed or made of different materials, or may be differently assembled. Some such casting process, with the use of 10 readily fusible metal, however, is preferred.

15 In the modification of Figs. 7, 8 and 9, the holder is formed from a single sheet of metal, somewhat like that shown in Fig. 9, with a middle rectangular part 9' to form the barrel, and smaller rectangular wings 20 8' and 8'' to form the neck when the part 9' has been bent around and these wings have been bent around and suitably connected at their upper and lower edges, as by the flanges 15 on the part 8' and the flanges 16 25 on the part 8'', bent over the flanges 15. The part 9' preferably has the screw-threads 10' pressed in it prior to forming, as shown in Fig. 9.

However the sheet-metal holder may be 30 constructed, it is especially adaptable to having a resilient piece to press inward on the piece of sparking material 13, as the tongue 17 formed by severing the middle portion of the part 9' close to the lower edge 35 of this part and in parallel lines up a considerable distance, leaving this tongue integral with the holder at its upper end, and slightly forming it to have a curved contact with the piece 13 very close to the bottom 40 of the holder. This formation leaves the very narrow band 18 at the bottom of the front of the holder, preventing spreading of the sides of the lower part of the holder barrel 9', but permitting the lower end of 45 the tongue to be bent slightly outward, for permitting ready passage of the piece 13 up into the holder, in renewing, while at the same time permitting the curved contact 19 to be far enough down to hold the piece 50 13 until most of it has been used. This resilient holding pressure is generally not essential, however, because the piece 13 may fit the holder socket-portion 11 in Figs. 1 to 6, inclusive, snugly enough to not readily 55 slide down out of the socket upon occasional, generally accidental, raising of the holder away from the file, against the pressure of the spring-controlled member 2. Except on such occasions, this pressure will prevent release of the piece 13 from the holder, without the use of any resilient holding means such as the tongue 17.

The cast, or otherwise solidly formed holder may be provided with resilient holding means, if desirable. An example of this

is shown in Figs. 10 and 11, where the cast holder 7^a has all of its parts like those of the holder 7 of Figs. 1 to 6, inclusive, except that there is a spring collar 20 imbedded in the casting in the lower part of the barrel 70 where would be the smooth portion 11 of the preceding example. This collar 20 is formed from a strip of sheet metal bent around but having its ends 21 not quite meeting, so that a narrow space 22 is left between them. This 75 collar can be formed so that it does not exactly conform to the interior of the barrel, and so that its free ends bend out as the material 13 is inserted, and thus grip the material with a yieldable pressure due to the 80 resiliency of the collar material. This construction is readily accomplished by placing the collar 20 around the core of the mold, leaving a slight feather on the core to fill the space 22 between the collar ends 21, so 85 that the metal is excluded therefrom in the casting. The imperfect attachment of the collar to the casting interior permits the slight play of the parts as just mentioned, yet is sufficient to retain the collar in the 90 holder. In this construction, the collar, of brass or the like, retaining its resiliency under the heat of casting, also acts as a wear-resisting bushing in the holder, where the renewals are inserted, thus adding to the 95 durability of the device.

The simple holder of soft cast metal, as in Figs. 1 to 6, inclusive, will, however, hold the material 13 satisfactorily, and will be durable enough for all practical purposes, 100 under most conditions, and is preferred. Also, other modifications may occur, under different conditions, besides those herein shown, and therefore, while certain constructional details are deemed preferable in 105 connection with my invention, and I have shown and described these rather specifically in elucidating the construction and use of my invention, as is required, I do not wish to be understood as being limited to 110 such precise showing and description, but having thus fully described my invention,

What I claim as new and desire to secure by Letters Patent is:

1. In a gas-lighter, a holder for spark-producing material having an opening through it from end to end, a screw threaded in one end part of said opening for bearing directly against spark-producing material in the other end part of said holder, a 115 support for said holder, attached to said holder substantially at right angles to said opening, an abradant entirely outside of said holder, and a support for said abradant, yieldably connected to said holder support, whereby the spark-producing material is continuously held against said abradant substantially at right angles to said abradant, to be dragged along said abradant, whereby said screw is adapted to adjust said 120 125 130

- spark - producing material against said abradant and said abradant tends to hold said material in said holder against said screw.
- 5 2. In a gas-lighter, a holder for spark-producing material comprising a barrel and a neck projecting from said barrel at a substantial angle thereto, having an opening in said neck receiving a supporting element, 10 and having an opening in one end of said barrel, and a resilient collar held in said barrel opening for retentively contacting with spark-producing material held in said opening.
- 15 3. In a gas-lighter, a supporting part, and a holder of soft, readily fusible material molded on said supporting part, and having an opening through it from end to end substantially at right angles to said supporting part, with threads molded in one end part 20 of said opening by means of a threaded core in the mold.
4. In a gas-lighter, a supporting part, and a holder of soft, readily fusible material molded on said supporting part, and having an opening through it from end to end substantially at right angles to said supporting part, with a screw threaded into one end part of said opening by being held in the mold during the molding process. 25

GAIUS C. FULLER.
